UNITED STATES PATENT OFFICE.

CLAS AUGUST SUNDBERG, OF STOCKHOLM, SWEDEN.

REGULATING DEVICE FOR GAS OR PETROLEUM MACHINES.

SPECIFICATION forming part of Letters Patent No. 594,042, dated November 23, 1897.

Application filed April 8, 1897. Serial No. 631,295. (No model.)

To all whom it may concern:

Be it known that I, CLAS AUGUST SUNDBERG, a subject of the King of Sweden and Norway, residing at Stockholm, Sweden, have 5 invented certain new and useful Improvements in Regulating Devices for Gas or Petroleum Machines; and I do hereby declare the following to be a full, clear, and exact description of the invention, such as will enable 10 others skilled in the art to which it appertains to make and use the same, reference being had to the accompanying drawings, and to letters of reference marked thereon, which form a part of this specification.

15 My invention relates to mechanism for regulating the opening and closing of valves, and more particularly to the feed-valves for naphtha, gas, and similar engines where the impelling fluid is to be fed not at the end of 20 each stroke, but at the end of a predetermined number of strokes of the piston; and it further provides for the governing of the engine by novel mechanism operating between the feed-valve spindle and the end of the eccentric-rod by the inertia of the reciprocating parts, and in the construction, combination, 25 and arrangement of parts hereinafter described, and particularly pointed out in the claims.

30 In the drawings, Figure 1 is a side view of my mechanism, partly in section. Fig. 2 shows the teeth on the cylindrical tappet developed, with successive positions of the reciprocating tappet-teeth shown in dotted lines. Fig. 3 is a detail showing the part K 35 in elevation, and Fig. 4 is an elevation of the governing-weight element.

Like letters of reference indicate like parts throughout the several views.

40 B is a valve rod or spindle having reciprocating motion in its support B', and to this support is fastened a coil-spring E', which serves to keep the valve normally closed and whose end bears on a cylindrical tappet E, 45 secured to the end of the valve-spindle by a pin F.

C is a fixed support serving as a guide for the spindle A' and having on its upper face a series of triangular teeth C', that engage 50 similar teeth D' on the lower end of the reciprocating tappet element D, which is revolvably mounted on the end of the spindle A'.

The upper end of the tappet element D is also provided with teeth D², having wedge-shaped ends or crowns that engage complementary recesses E² in the crowns of teeth E³ of the upper tappet-cylinder E. A portion of the end of the spindle A' is cut away, so as to form two shoulders H and I, the lower one, H, of which is provided with a buffer-spring y 60 and tension-nut y'.

The eccentric-rod A has hinged to its end a bell-crank lever K, whose longer arm normally engages the shoulder H in the spindle A' and thereby lifts the tappet D; but when 65 the engine is running too fast—i. e., above normal—this arm of the bell-crank lever engages the shoulder I, or, rather, slides on the surface between H and I, and does not lift the spindle A' with its attached tappet-cylinder D. The shorter arm of the bell-crank lever has hinged to it at P a weighted angle-lever W, whose vertical arm O has a pin R', 70 that serves to hold it in engagement with a buffer-spring R, adjustably secured in the eccentric-rod by a screw S and nut T, while the free end of the arm O engages a shoulder U 75 on an arm or guide V, which is yieldingly held in the fixed support Z by a pin X and spring x. The support Z also serves to guide the end of 80 the eccentric-rod A. The opening of the valve at the end of a predetermined number of strokes is dependent on the formation and relative arrangement of the tappet-teeth.

In Fig. 2 I have shown the surfaces of the 85 respective tappet-cylinders developed and in dotted lines the successive positions of a pair of teeth of the reciprocating tappet D, which is to open a valve at every other stroke of the eccentric when the engine is running normal. 90

Supposing the eccentric just about to begin its stroke to open the valve, then the several sets of tappet-teeth will be in the position shown in full lines, Fig. 2. On moving forward the teeth D² of the reciprocating tappet D will be moved to contact with the teeth E³ on the end of the valve-spindle, as shown in dotted lines at 4. The continued movement will cause the teeth D² to strike fully into the notches E² in the crowns of the teeth E³ by 100 virtue of the beveled surface in contact, it being remembered that the element D is revolvably mounted on the end of the spindle A', and will turn the tappet D slightly on its axis

and throw its triangular teeth D' out of register with the teeth C' on the support or guide C, as shown at 5. The continued movement of the eccentric will now lift the tappet E and valve-spindle to open the valve, as shown in the position marked 3. Now on the return stroke, the triangular teeth being out of register, the reciprocating tappet D will drop to position shown at 6, contact with and slide down the teeth C', and be turned on its axis the distance of one tooth to the position marked 7. The next forward stroke brings the upper teeth D² into the position marked 8, when they strike the beveled faces F² of the teeth E³, slide over these surfaces into the spaces between the teeth E³ and into the position marked 9, the triangular teeth being consequently again thrown out of register, and the continued stroke of the eccentric simply forces the teeth D² up into the spaces between the teeth E³ without lifting the valve. On the return the triangular teeth again slide over one another, as above described, and the reciprocating tappet is ready to lift the valve again.

For governing the engine the mechanism between the end of the eccentric-rod A and spindle A' is used and operates as follows: The too rapid motion of the eccentric-rod will cause the weight N, in consequence of its inertia, to leave its normal position and to fall back to said normal position after the rod A has completed its stroke. Hence the arm O does not engage the shoulder U, but drops down along the element V, causing the longer arm of the bell-crank lever K to leave the shoulder H and ride on the surface between H and I, thus preventing the operation of the spindle A' and tappet D and leaving the valve closed. Upon resuming normal speed the arm O will again engage the shoulder U and throw the longer arm of the bell-crank lever K again into the engagement with the shoulder H in position for operating the tappet mechanism and valve.

Having thus described my invention, what I claim as new therein, and desire to secure by Letters Patent, is—

1. A spring-closed valve, its spindle end provided with a toothed tappet adapted to have axial motion thereon, in combination

with a revoluble tappet - cylinder provided with teeth at either end, a guide for the spindle of the revoluble tappet having teeth on its face, said revoluble tappet adapted to be revolved by engagement with the aforementioned toothed tappet and the teeth on the guide, substantially as and for the purpose set forth. 55

2. A spring-closed valve provided with an axially-movable toothed tappet on its spindle end, in combination with a double - ended toothed tappet revoluble on its spindle, a guide for said spindle having teeth on its face, the teeth of these respective co-operating elements so formed as to turn the revoluble tappet by its alternate engagement with the guide-face and axially-movable tappet, substantially as and for the purpose set forth. 65

3. In a valve - operating mechanism substantially as described, a tooth-faced guide, an axially-movable tappet provided with a set of teeth out of register with the series of teeth on the guide - face, the intermediate double-ended toothed tappet adapted to alternately engage both series of teeth and thereby receive a step-by-step rotation, for the purpose set forth. 70

4. In a valve-operating mechanism, a governor comprising a bell-crank lever hinged to the end of the eccentric-rod, a weight hinged to one arm of said lever, an arm perpendicular to said weight and normally having sliding contact with a guide-piece, substantially as set forth. 80

5. In a valve-operating mechanism, a governor comprising a bell-crank lever hinged to the end of the eccentric-rod, whose longer arm operates a tappet when running normal, a weight hinged to its shorter arm, an arm extending from said weight, a buffer-spring between the eccentric-rod and the aforementioned arm, and a yielding guide, provided with a notch at the end of a guide-surface thereon, into which the arm extending from the weight slides, substantially as set forth. 85 90

In testimony whereof I affix my signature in presence of two witnesses.

CLAS AUGUST SUNDBERG.
